GLASSWARE FORMING MACHINE

Charles R. Vining, Elmore, and Irvin C. Hamilton,
Toledo, Ohio, assignors to Libbey Glass Com-
pany, a corporation of Ohio

Application March 20, 1939, Serial No. 262,820

6 Claims. (Cl. 49—37)

The present invention relates to improvements in glassware forming machines and more especially to apparatus for shaping and affixing the foot or base portions to tumblers and like articles of tableware.

An object of the invention is the provision of automatic means for shaping and simultaneously attaching the foot or base portions to tumblers. To this end the invention is embodied in a continuously rotating machine which in somewhat less than a single revolution, receives and transforms a measured charge of molten glass into a foot or base portion, attaches it to a tumbler bowl and marvers the glass and finally positions the completed article for removal, the latter being effected manually or mechanically as may be desired.

It is also an object to provide means whereby the machine may with comparative ease be adjusted to operate upon ware of different sizes.

Other objects will be in part apparent and in part pointed out hereinafter.

In the drawings:

Fig. 1 is a front elevational view of one of the heads of the forming machine;

Fig. 2 is a fragmentary plan view with parts in section illustrating the individual head construction at different elevations;

Fig. 3 is a vertical transverse sectional view through the complete machine;

Fig. 4 is a vertical sectional elevational view taken substantially along the line 4—4 of Fig. 1;

Figs. 5, 6 and 7 are sectional views illustrating the successive steps involved in the foot forming and attaching operation. Fig. 5 shows the mold charge prior to its being pressed into final shape. Fig. 6 illustrates the manner in which the pressing heading spaces the mold charge. Fig. 7 shows the complete assembly and the mold parts removed from contact with the glass.

Fig. 8 is a fragmentary sectional elevational view of the means for adjusting the chuck and operating mechanism therefor vertically to compensate for differences in the length of the glassware being fabricated;

Fig. 9 is a detail sectional view of the mechanism for manipulating the foot pressing head; and

Fig. 10 is a sectional view taken substantially along the line 10—10 of Fig. 9.

Our invention is embodied in a rotary type machine which includes a wheeled base 15 of drum-like formation, the vertical outside wall 16 of which supports stationary cams and a ring gear, the functions of which will become apparent here-

inafter. A stationary central column 17 rises axially from the base and at its upper end carries a spider 18 intended to support another stationary cam, the functions of which will become apparent hereinafter. A rotary carriage 19 is mounted upon the base 15 for rotation upon anti-friction bearings 20, which may well be the conventional ball bearings positioned at the periphery of the base and carriage.

Continuous rotation of the carriage 19 is obtained by means of an electric motor 21, which drives the carriage through a speed reduction gearing 22 and pinion 23, the latter running in mesh with a ring gear 24 which forms a part of or is rigidly attached to the under side of said carriage.

The hub portion of the carriage and base are constructed to provide a continuous annular air chamber 25 to which air under pressure is supplied through a pipe 26 and from which air is conducted to the several heads of the machine, for a purpose to be described, by means of pipes 27, which are individual to the heads.

An annular series of foot forming and attaching heads are mounted upon the peripheral portions of the carriage 19 and through rotary movement of the latter, are caused to travel through several zones or positions, wherein the steps, making up a complete cycle of operations, are performed. Inasmuch as all of the heads are identical in construction and operation, the following detailed description will be directed to one head only.

Each head includes a bowl supporting chuck unit 28 and a foot or base forming unit 29, said chuck being adjustable vertically with respect to the foot forming unit so as to adapt the machine to the manufacture of footed tumblers of different heights.

The bowl supporting unit includes a vertical bracket 30 carried by a slide 31 which is mounted in opposed vertical guideways 32, the latter being provided at the margins of a carrier 33. This carrier includes an inwardly directed arm 34 at its upper end which takes over and is removably attached to the carriage 19. Adjustment of the slide and parts carried thereby is obtained through the medium of a vertical, threaded adjusting rod 35, which is journalled in bearings 36 and is threaded through a lug 37 carried by the slide 31. The upper end of the adjusting rod is operatively connected to a manually actuated crank 38, or hand wheel, through means including a pair of meshing bevel gears 39. Through this mechanism the bowl supporting unit may be

adjusted to compensate for variations in the length of the tumblers being fabricated.

The chuck 40 for supporting the bowls B, includes a pair of jaws 41 which are mounted upon a horizontal hinge pin 42 at the upper end of a push rod 43 and also are connected through links 44 to the upper end of a tubular drive shaft 45. This drive shaft encloses a major portion of the push rod 43 and forms a guide therefor. Furthermore the tubular shaft 45 is reduced in diameter in proximity to its upper end, the reduced portion being journaled in a bearing 46 provided at the upper end of the bracket 30. That portion of the tubular shaft 45 which is disposed below the bearing 46 and above the lower end of the bracket 30, is provided externally with gear teeth extending from end to end and running in mesh with a pinion 47, which in turn meshes with an annular ring gear 48, the latter being carried by the base 15. Movement of the head circumferentially of the base very obviously results in rotation of the chuck 40 and the bowl B supported therein.

Opening and closing of the chuck jaws 41 is effected by vertical movement of the push rod 43, such movement being obtained automatically at regular time intervals by mechanism including a pneumatically actuated tappet unit 49. This unit consists of a cylinder 50 and a piston 51 mounted therein, said piston carrying a rod 52 which is continuously engaged with an adjustable extension 53 on the bottom end of the push rod 43. A sleeve 54 interposed between the extension 53 and a coil spring 55, which encircles the push rod between the aforementioned tubular shaft 45 and the guide 56 at the lower end of the bracket 30, functions as a part of the mechanism providing operative connection between the tappet and push rod. As is obvious, the connection is yieldable and to a greater or lesser degree precludes the possibility of exerting excessive pressure upon that portion of the bowl which is gripped by the chuck jaws 41. Actuation of the tappet 49 is obtained by the application of air under pressure flowing to the bottom end of the cylinder 50 by way of the aforementioned pipe 27 and a cam actuated valve 57. This valve includes a plunger type control 58 which at regular time intervals is brought into engagement 50 with a stationary cam 59, the latter being mounted upon the base 15.

The foot forming unit includes a pair of mold sections 60 which are separably attached to holders 61, the latter being mounted upon radial arms 62 which are carried by a pair of slides 63. These slides which are placed on edge and mounted for horizontal movement relative to each other, are supported in vertically spaced slideways 64 or guides, which extend tangentially relative to the periphery of the carriage 19. Brackets 65 rigidly support the guides upon the carriage. A coil spring 66 connects the two slides 63 and continuously exerts a pressure tending to bring the mold sections 60 into engagement with each other. A spreader or mold opener 67 is positioned between the inner ends of the slides for the purpose of separating the mold sections 60 at regular time intervals. The spreader is mounted upon a short shaft 68 which extends 70 radially inward therefrom and carries a bell crank lever 69. The free end of the bell crank lever carries a roller which runs in a continuous box cam 71, the contour of which predetermines the points at which the foot forming 75 molds open and close.

The mold sections 60 are provided centrally with a vertical opening 72, the dimensions and shape of which correspond to those of the base of the bowl B and short neck portion which connects the bowl and foot proper. The upper end 5 of this opening 72 merges into a shallow cavity 73 which corresponds in shape and dimensions to those of the upper surface of the foot F. The mold is completed by means of a pressing head 74 which includes a holder 75 and a block 76, 10 the lower face of which is shaped for cooperation with the mold sections 60 in the completion of the mold cavity and shaping of the foot F.

Operation of the pressing head 74 is synchronized with the opening and closing movements 15 of the mold sections 60. The mechanism for manipulating the pressing head consists of an arm 77 which has yielding and adjustable connection with a threaded rod 78 which forms a part of the head 74. This arm is adjustably 20 mounted upon the upper end of a rod 79 which is partly enclosed in a tubular housing 80, the latter being bolted to the carriage. The lower end portion of this rod 79 extends into a sleeve 81, said sleeve having a circumferential slot 82 25 which registers with an elongated slot 83 formed in and extending lengthwise of the housing 80. These slots register with each other and accommodate rollers 84 which are suitably mounted upon the lower portion of the rod 79. An inwardly directed arm 85 at the lower end of the sleeve 81 carries a cam roll 86, which at regular time intervals, is engaged by a stationary cam 87, the latter operating to move the sleeve 81 and rod 79 downwardly. Such downward movement of these parts relative to the housing 80, together with rotary movement of the rod 79, due to the outer roller 84 following the path of the curved slot 83 in the housing, brings the pressing head 74 into axial alignment with the 40 closed mold sections 60. A key 88 (Fig. 9) carried by the housing 80 and running in a keyway 89 in the sleeve 81, holds the latter against rotation relative to the housing during axial movement thereof. A coil spring 90 positioned within 45 a sleeve 91 at the upper end of the housing normally tends to hold the arm 77 in its uppermost position. It will be observed that this sleeve 91 is threaded upon the upper portion of the rod 79 and that the spring 90 is held between the 50 upper end of the sleeve 91 and a washer 92 which is supported by screws 93 or the like, extending into the housing.

Adjustment of the arm 77 upon the rod 79 may be obtained by rotation of a knurled adjusting nut 94 as is obvious.

Operation of the machine involves continuous rotation of the carriage 19 so that the forming heads are moved in succession past several stations. At one station, or position, a tumbler bowl B is placed in an inverted position between the jaws of the bowl supporting unit 40. Immediately the jaws 41 are closed about the constricted neck portion. In a succeeding zone the foot mold sections 60 are brought together substantially as shown in Fig. 5 and thereafter a measured charge C of molten glass is deposited centrally of the mold cavity in contact with the closed end of the bowl. In the next position the pressing head is swung radially outward and 70 lowered to complete the mold cavity and simultaneously press the molten glass to its final shape and effect permanent attachment thereof to the bowl. During these operations the chuck rotates about its axis continuously so that the glass 75

forming the foot is ironed or marvered. After the glass has set sufficiently, the pressing head is elevated and moved radially inward of the machine and the foot mold sections 60 are separated, leaving the bowl and attached completed foot supported in the chuck 40. Following this operation the chuck is opened and the article removed therefrom manually, or by a mechanical device, many of which are available for this purpose.

Modifications may be resorted to within the spirit and scope of the appended claims.

We claim:

1. Glassware forming apparatus comprising a bowl supporting chuck, a foot forming and attaching unit positioned above the chuck, said unit including horizontally separable mold sections, a pressing head arranged for cooperation with said mold sections, means for effecting synchronized operation of the chuck, mold sections and head, means for effecting relative rotation of the chuck and said unit, a slide supporting the chuck and manually operable means for adjusting the slide vertically relative to said unit.
2. Glassware forming apparatus comprising a bowl supporting chuck, said chuck consisting of a pair of separable jaws, means normally yieldingly holding the jaws closed, pneumatic means for separating the jaws, means for imparting rotary movement to the chuck about its longitudinal axis and a foot forming and attaching unit positioned above and individual to the chuck, said unit including a pair of mold sections, a pressing head normally disposed above said sections and automatic means for operatively positioning said head relative to the mold sections at regular time intervals.
3. Glassware forming apparatus comprising a bowl supporting chuck, said chuck consisting of a pair of separable jaws, means normally yieldingly holding the jaws closed, pneumatic means for separating the jaws, means for imparting rotary movement to the chuck about its longitudinal axis, a foot forming and attaching unit positioned above and individual to the chuck, said unit including a pair of mold sections, a pressing head normally disposed above said sections, automatic means for operatively positioning said head relative to the mold sections at regular time intervals, horizontally movable supports for the mold sections, spring means normally holding the sections closed, and automatic means for separating the supports and mold sections at times.
4. Glassware forming apparatus comprising a bowl supporting chuck, said chuck consisting of a pair of separable jaws, means normally yieldingly holding the jaws closed, pneumatic means for separating the jaws, means for imparting rotary movement to the chuck about its longitudinal axis, a foot forming and attaching unit positioned above and individual to the chuck, said unit including a pair of mold sections, a pressing head normally disposed above said sections, automatic means for operatively positioning said head relative to the mold sections at regular time intervals, horizontally movable supports for the mold sections, spring means normally holding the sections closed, and cam controlled means for separating the supports and mold sections at regular time intervals.
5. Glassware forming apparatus comprising an annular series of heads mounted for rotation about a vertical axis, means for imparting continuous rotary movement to the heads, each head including a vertically disposed bowl supporting chuck, means for rotating the chuck about its vertical longitudinal axis, a foot forming and attaching unit positioned above the chuck, said unit including a pair of mold sections separable along a line extending tangentially of the path of travel of the heads, a pressing head positioned above the mold sections and adapted for cooperation therewith in pressing and finally shaping a foot portion and automatic means actuated by rotation of the heads for effecting synchronized operation of the chuck, mold sections and pressing heads.
6. Glassware forming apparatus comprising a vertically disposed bowl supporting chuck, means for rotating the chuck about its vertical longitudinal axis with a bowl supported therein in an inverted position, a foot forming and attaching unit spaced above said chuck, said unit including a pair of horizontally separable sections having a central opening and a cavity provided in its upper side and merging into said central opening, a pressing head disposed above the mold sections, and means for bringing the pressing head into position for cooperation with the mold sections in pressing a foot and attaching it to the bowl, said last named means including a stationary cam and a yielding support for the head adapted to be actuated by said cam.
